UNITED STATES PATENT OFFICE

1,993,788

FIRE PREVENTION SYSTEM

Irvin E. Hunter, East Braintree, and Chester W. Johnson, Weymouth, Mass.

Application November 22, 1932, Serial No. 643,888

4 Claims. (Cl. 177—311)

In the prevention of fire hazards and particularly in the precombustion stage of fire development, there has been recognized for a long time the potential warning value of smoke fumes, but most of the present systems of smoke detection in practical use depend on sight or smell and hence involve the factor of human error, failure or neglect.

Under certain conditions mechanical or automatic detection has seemed impossible. For example, on shipboard where multiple holds are loaded or in the process of being filled by grain, cement, ore or like friable binder, there is a definite dust factor. This is common also on land.

As the fire hazard at dock is really a more serious one than at sea, the loading period is of much concern. The presence of unorganized loading workers is a fire factor not under the check and control of an organized crew on duty.

The dust problem is also important on land in all sorts of buildings whether residences, offices, factories or stores. Dust, soot or other accumulative film forming air impurities are common in different places and at differing times. These even if slight and intermittent tend to accumulate and be a source of false alarms.

The use of the photoelectric cell has long been indicated as a logical basis of smoke detection. However, the important efficiency of light ob- 30 scurance by such means has been nullified among other causes by the common occurrence of dust or other media present in the air and tending to form films on parts that must be kept at standard transparency.

Such conditions together with those necessarily involved comprise the problem. Our concept is based on a simple and efficient system of control and mechanism to solve it.

While marine conditions are of specific importance and generally illustrative, the ordinary fire hazard is equally present on land. We therefore wish to be considered as operating within all reasonable lines of activities on land as well as at sea.

According to another phase of our concept we provide our system for the detection of gases. Many gases are poisonous or explosive or both, and on account of their normal invisibility constitute a great menace especially in conjunction with fire. These and other features we provide for by simple and effective systems and apparatus which we so combine as to safeguard against all emergencies.

Throughout the specification and drawings like

reference numerals are employed to indicate corresponding parts, and in the drawings:

Fig. 1 is a front elevation of the detection or central station cabinet.

Fig. 2 is a view from the left of the special cabinet as shown in Fig. 1, with casing partly broken away.

Fig. 3 is a similar view from the right of Fig. 1.

Fig. 4 is a detail of a section of the vent and alarm system.

Fig. 5 is a face view of the collector vent funnel with the thermal unit encased, and

Fig. 6 is a diagrammatic view of the wiring system.

The illustrative equipment shown in the drawing consists of a collector system comprising tubes 2 run on ceilings or below decks to all rooms, compartments or holds that are or might be danger spots.

Spaced along the tubes are the collectors 1 of inverted funnel or bell shape into which the surrounding air is continuously drawn so that any smoke—even from a small local smouldering—will be caught and sucked into and through the tube of the system.

Suction is maintained by a pump F preferably located with the rest of the detection apparatus at the central station which on shipboard would be the pilot house or like place of authority and source of emergency action. The pump F is preferably continuously operating.

While our system is essentially a smoke detector, it combines with it a thermal auxiliary. For this we utilize the collectors 1 as casings for thermostats 4 which are supported by screens 6 over the collector mouths.

The collector tubes 2 are supported principally by hangers 5 slightly spaced from the ceiling or other point of elevation to which the smoke would rise.

The thermostats 4 have their contact members connected each with one of a pair of electrical conductors preferably in armoured cables 3 and in protected relation. These are supported in the hangers 5 one on each side of the conductor 2 and connect with an audible or visible signal such as a bell or red light (not shown) or both.

Such a collector and alarm line is inconspicuous and self protecting and can be economically installed, moved or added to as desired.

The various collector tubes 2 are connected to a manifold on the intake tube R of the pump F. As shown in Fig. 1 the pump F is mounted in a cabinet being directly coupled to a variable speed motor G, a transformer H and binding

posts Y are indicated at the left of the motor. Variable resistors J¹, J², J³ are also mounted on the cabinet panel together with the auxiliary relay K, the cell relay M and the filament selector relay N¹ and safety relay N².

The pump F draws up through the collector funnels and discharges through an exhaust tube S into a filter E. Its end is carried well down toward the filter bottom and preferably perforated. From the filter an exhaust tube T having a relief valve V leads to the smoke chamber B which is provided with a vent tube U.

The relief valve V is independent of the vent tube U and permits excess quantities of air or smoke to be collected and pumped so that the smoke chamber is always fully supplied. Thus when the pump is speeded up the smoke laden air from any remote part is brought more quickly to the smoke chamber and detection is hastened. The filter might be supposed to slow up detection, but any lag in the filter can be met by speeding up the motor.

The smoke chamber B is a cylindrical box having transparent ends or windows b which if the chamber be free of smoke permit light from the lamp house A to pass through the chamber and fall on photronic cell C of any desired construction.

The lamp house is provided with a double source of light. As shown in Fig. 1 this may be a pair of bulbs or as indicated in the wiring diagram in Fig. 6 may be a single bulb with a double filament. In either case upon the failure of one light source the other automatically comes into operation and at the same time operates a signal call for replacement. This is substantially in accordance with our prior application Serial No. 611,220, filed May 13, 1932.

Our filter E is charged with finely divided material such as crushed stone coated with an adhesive tacky dust arresting material, such as non-drying oil, or thin tar mixture having a softener resistant to drying. The filter bed thus formed has been found by experiments effectively to arrest all ordinary dust but readily to permit the passage of smoke therethrough, this being due presumably to ordinary dust particles being considerably larger than the infinitesimally small particles of carbon comprising smoke. Other experiments have demonstrated that if the filter is supplied with water instead of oil or the like, dust is arrested and smoke is permitted to pass.

At Q we have indicated a perforated container covering the end of the exhaust tube T. In this container we provide a dry material reactive with the suspected invisible gas to make it visible as a dark or colored fume capable of obscuring the light in the smoke chamber B and thus operating the device in the same manner as the smoke itself if present.

In the electric circuit 14 of the photronic cell C is a relay 15 which operates a switch 16 located in a circuit 17 provided with an auxiliary relay 18. The circuit 17 has a booster battery 19 therein and the auxiliary relay actuates a switch 20 which closes the circuit with the line 21 from the main switch 22 with the wire 23 leading to a signal 24 located at some convenient point to give warning when the apparatus indicates that a fire exists within the building.

The two filaments (or two lamps) 12, 13 of the projecting lamp 11 connect with the wire 25 leading to a transformer 26 in the wire line 21 leading from the signal 24 to the main source of

electricity which is indicated as having an alternating current of 110 volts. By means of the transformer 26, the voltage in the wire 25 leading to the filaments 12, 13 is reduced to some suitable low voltage such as ten volts.

In the line 25 is a variable resistance 27 which is used to adjust the lamp for the proper illumination. The line 28 leads from the transformer 26 to a safety relay 29 and from the safety relay 29 to a wire 30 leads to two test switches 21 and 32. The safety relay 29 is controlled by a switch 33 adapted to make and break the circuit in the wire line 17. The test switch 31 is connected to the filament 12 by a wire 34 in which is a filament selector relay 35.

This selector relay 35 has associated therewith a switch 36 in the wire line 37 between the test switch 32 and the filament (or lamp) 13 and in this line 37 is a variable resistance 38 which may be adjusted so that the illumination of the two filaments 12, 13 will be of the same intensity.

When either filament 12 or 13 is in commission the switches 22, 31, 33 and 32 will be closed and when the filament 12 is in commission the filament selector relay 35 will be open. Should the filament 12 burn out no current will flow through the filament selector relay 35 and this relay 35 will actuate the contact points of the switch 36 to allow the current to pass through the filament 13.

The contacts on the photoelectric cell C and auxiliary relays are always open except when the light beams are interrupted by smoke entering the chamber B disposed between the light source and photoelectric cell.

Should both filaments or lamps burn out, or if power is interrupted for any other reason, the contact of switch 33 connected to the safety relay 29 will open and thus prevent the operation of the auxiliary relay 18 and the apparatus will remain out of commission until a new lamp 11 is installed in place of that burnt out. During this time, however, the thermal alarm is effective as the pump is kept running so that thermal alarm while combined with a part of the smoke detector system may be in a sense considered an independent auxiliary and be kept on all day when the smoke detector is not usually needed.

During the day or when the building is occupied by workmen, the switch 22 is open and no current flows to the lamp 11, but when the workmen leave the building the main switch 22 is closed permitting the electric current to flow through the various wire lines to the projecting lamp 11.

Each filament or lamp is tested by means of the test switches 31 and 32 to ascertain if both are in working condition. The light beams in the lamp 11 will be directed into the photocell unit C and the entire apparatus is ready for action in case of a fire.

The lamp or lamps and the lenses b of the smoke chamber B and 10 must be kept clean by brushes or cloth manually moved over the faces of the lenses.

What we therefore claim and desire to secure by Letters Patent is:—

1. Means for utilizing smoke emanating from a fire to detect the presence of the fire, said means comprising a photoelectric cell, means providing a source of light spaced from said cell and having a light beam falling thereon, an electric alarm system under the control of said cell, said system including means whereby the alarm is maintained inactive when the light strikes the

5

10

15

cell and is rendered active when the light is obscured or is reduced a predetermined amount in intensity, means for conducting and inducing a flow of air and smoke, if the latter is present, from a location of possible fire through the space between said cell and said source of light so that if smoke is present the light is obscured or reduced in intensity sufficiently to cause the cell to render the alarm system active, and a filter in the air and smoke conducting means between said space and the location of possible fire, said filter being effective to permit the passage of smoke and to effect the removal from the air of dust of a character which, if present in the air, would obscure or reduce the intensity of the light sufficiently to cause the cell to render the alarm active.

2. Fire detection means as set forth in claim 1 in which a chamber having a smaller outlet than inlet and transparent windows for the passage of

the light is provided in the air and smoke conducting means at a point between the source of light and the cell for the accumulation of smoke.

3. Fire detection means as set forth in claim 1 including means in the air and smoke conducting means reactive with invisible gases to render them visible as a dark or colored fume capable of affecting the cell in the same way as smoke.

4. Fire detection means as set forth in claim 1 including means in the air and smoke conducting means reactive with invisible gases to render them visible as a dark or colored fume capable of affecting the cell in the same way as smoke, said reactive means being disposed to react with the gases after their passage through the filter and prior to their passage through the space between the cell and the source of light.
